AIRPLANE

Martin Jensen, New York, N. Y., assignor to
Langley Aviation Corporation, New York, N. Y.,
a corporation of Delaware

Application September 2, 1942, Serial No. 457,077

1 Claim. (Cl. 244—60)

This invention relates to airplanes and in particular to airplanes having propulsion systems of multi-motor, contra-turning propeller type.

An object of the invention is to provide a compact, simple, and efficient system including the feature, preferably, that the drive of all of the engines goes to all of the propellers.

While the invention is not necessarily limited as to the type of engine used, its advantages may be realized to the fullest extent when double-bank pancake type engines mounted flatwise in wing cavities are employed. In the use of such engines the normal wing section need not be disturbed and since excrescences for the housing of the engines are thus avoided, parasite resistance is accordingly lessened. Utilizing the wing-contained pancake engines, the new system permits the weight of the engines to be effectively centralized and disposed for high maneuverability. Consequently, the invention finds particular applicability in the case of planes of combat type where speed and maneuverability are essential. Efficiency and maneuverability are further enhanced by the contra-turning propellers.

In the further description of the invention, reference will be made to the accompanying drawings, which show the new arrangement in illustrative embodiment. In these drawings:

Figure 1 is a plan view of a single seater monoplane of fighter type embodying the invention.

Figure 2 is a front elevation of the airplane of Figure 1.

Figure 3 is an elevation of the airplane as seen from the left hand side with the left hand wing in section on the line 3—3 of Figure 1, and

Figure 4 is an enlarged plan view of a gear box whereby the engines are connected to the propeller shafts, the top of the gear box being removed.

The illustrated airplane has a main plane including the right and left hand wings 10 and 11 which extend from a fuselage 12. The fuselage includes a forward extension or nose portion 13, a central portion 14 in which the cockpit is disposed, and a tail portion 15 which supports the usual empennage 16. The roof 17 of portion 15 is elevated above the roof of the forward portion and the latter is faired into the former by a transparent windshield 18 at the cockpit. The airplane is provided with a tricycle landing gear including the struts 19 and 20 beneath the wings and the strut 21 beneath the forward portion 13. In flight the struts 19 and 20 can be moved toward the fuselage and then swung outwardly and upwardly to bring the wheels 22 and 23 into

cavities on the undersides of the wings as indicated in Figure 1. The strut 21 is adapted to be swung upwardly and rearwardly in order to bring the wheel 24 into a suitable cavity at the underside of the fuselage.

Two double-bank pancake type engines 25 and 26 are arranged flatwise in the wings 10 and 11, respectively, immediately adjacent the fuselage with their crank or power shafts 27 and 28 in alignment and with their output ends adjacent each other. Preferably, and as here shown, the common axis of the engines is coincident with the lateral axis 29 of the aircraft so that the engines are substantially balanced about this axis. The power shafts 27 and 28 extend into the fuselage and into a gear box 30 disposed substantially at the center of gravity and have bevel gears 31 and 32 of like size fixed on their respective extremities within the box. Overrunning clutches 33 and 34 are interposed in shafts 27 and 28 respectively.

Journaled in the forward wall of the gear box, is a hollow propeller shaft 35 and within the box 30 shaft 35 has fixed thereon a bevel gear 36 which engages both the gears 31 and 32. Propeller shaft 35 extends forwardly on the longitudinal axis of the airplane as here shown, its forward portion being supported in a bearing 37 and its extremity having fixed thereon a propeller 38. A hollow propeller shaft 39 is disposed coaxially with, here shown as concentrically within, shaft 35 and projects beyond both ends of the latter. The rear end of shaft 39 is journaled in the rear wall of box 30 and within the box has secured thereon a bevel gear 40 of the same size as gear 36 and engaging both of gears 31 and 32. The forward portion of shaft 39 is rotatable in a bearing within shaft 35 and within bearing 31, and the forward extremity of the shaft 40 has fixed thereon a propeller 41.

The power shafts 27 and 28 are similarly rotating, and by this I mean that both shafts rotate either clockwise or counterclockwise when viewed from their output ends. This is an important feature of the invention, since it follows that the engines can be interchangeable. As indicated by arrows in Figure 4, the shafts 27 and 28 rotate counterclockwise and through the intermediary of the engaged bevel gears the propeller shafts 35 and 39 will be driven counterclockwise and clockwise, respectively, as seen from the front, and at the same speed, driving the propellers 38 and 41 in opposite directions.

If one engine should fail, it should be cut out, since otherwise it would have to be driven by

the remaining engine. It is for this reason that I provide means such as the overrunning clutches 33 and 34 in advance of gears 31 and 32. Upon the failure of either engine it will be immediately disconnected from the drive gearing as the other engine continues to drive both of the propellers.

The described arrangement permits the engines to be located close to the longitudinal axis of the airplane, and while I have shown them just to the sides of the fuselage, their adjacent ends might be in the latter to some extent. In any event, the width of the fuselage need be only sufficient to accommodate the pilot, the narrow fuselage enabling the air resistance of this member to be kept at a minimum. By using the pancake type engines disposed entirely within normal wing sections, the parasite resistance of special nacelles, cowling, etc., is eliminated, and visibility is enhanced. Access may be had to the engines through removable wing panels. With the weights all centered about the center of gravity, at which the engine axes intersect the axis of the propeller shafts, a highly maneuverable plane is made possible.

Struts 19 and 20 of the landing gear, it will be observed, are under the outer portions of the engines so as to be able to take their weight in landing.

In the case of a fighter plane, a cannon or gun 42 may be mounted with its breech portion in the cockpit immediately behind shaft 39 and with its barrel extending with clearance through the latter. The breech portion is readily accessible to the pilot's seat 43, as indicated in Figures 1 and 3.

The described arrangement of parts with reference to the center of gravity is the most satisfactory but the invention is not necessarily limited thereto. The engines should be substantially balanced on opposite sides of the vertical central longitudinal plane, but their axes can be outside the lateral axis of the airplane. The axis of the propeller shafts may be non-coincident with the longitudinal axis of the airplane, although it should be substantially in the vertical central longitudinal plane of the craft. In the drawings the engines are shown as being entirely in the wings, but, as has been mentioned, their adjacent ends may extend into the fuselage to further concentrate their weights in the vicinity of the center of gravity. With the described narrow fuselage, the engines will be at least partly in the wings and I intend to include such disposition in speaking of engines mounted in the wings. While the

engines and wings are preferably of such design and so related that the normal wing section is not disturbed, in some cases wing enlargements, top and/or bottom may be necessary for accommodation of the engines. I contemplate this factor also in speaking of engines mounted in the wings.

The invention is not concerned with any particular means for taking the propeller thrust, and any suitable system may be adopted.

Variations in the form and arrangement of parts from the illustrative disclosure herein are contemplated under the following claim, as will be understood. In stating that the output ends of the engine power shafts are adjacent each other I do not refer to propinquity, but mean merely that the engines are opposed with the output ends of their power shafts directed toward each other. In speaking of the axis of the propeller shafts as extending transversely of the power shaft axis, 10 intersection is not necessarily implied. The term "main plane," unless modified, is intended to cover wings with interposed fuselage, as shown, or a plane uninterrupted by a fuselage. The term "fuselage" is used as including a body, such as a nacelle, which does not run to the tail surfaces.

I claim:

In an airplane, a fuselage, a main plane comprising wings extending from the sides of the fuselage, a pair of similarly rotating pancake type engines arranged flatwise in said wings respectively at opposite sides of the central vertical longitudinal plane of the airplane and having substantially aligned power shafts with output ends extending into the interior of the fuselage, a pair 30 of concentric propeller shafts arranged substantially in the central vertical longitudinal plane of the airplane with their input ends in said fuselage adjacent said output ends, the opposite ends of said propeller shafts projecting longitudinally of the fuselage for the mounting of propellers thereon, a gearing assembly in the fuselage substantially at the center of gravity of the airplane connecting said output ends with said input ends whereby the propeller shafts are driven in opposite 40 directions; said gearing assembly including bevel gears respectively driven from and in the same direction as said output ends, and bevel gears on said input ends respectively and both engaged by each of the first-mentioned gears; and overrunning clutches in the drives between said engines respectively and said propeller shafts.

MARTIN JENSEN.
